UNITED STATES PATENT OFFICE.

MARTIN JELALIAN, OF CRANSTON, RHODE ISLAND.

MANUALLY-OPERATED BUFFING DEVICE FOR THE INNER FACES OF RINGS.

1,387,778.

Specification of Letters Patent. Patented Aug. 16, 1921.

Application filed November 18, 1920. Serial No. 425,022.

To all whom it may concern:

Be it known that I, MARTIN JELALIAN, a citizen of the United States, residing at the city of Cranston, in the county of Providence and State of Rhode Island, have invented certain new and useful Improvements in Manually-Operated Buffing Devices for the Inner Faces of Rings, of which the following is a specification.

10 The object of this invention is to improve the buffing manner of the inner faces of rings, providing a manually operated buffing device operated by crank shafts.

15 The parts of the device are so arranged that the same are readily and safely operated and by the operation of the same an unusual amount of work may be obtained.

20 The detailed description of the invention is illustrated in the accompanying two sheets of drawings forming a part of this specification, in which:

Figure 1 is a side perspective view of the device. Fig. 2 is a top plan view of Fig. 1. Fig. 3 is an enlarged side view of a strap 25 holder clip. Fig. 4 is an enlarged side perspective view of a casing device for setting rings, to buff the inner faces of the same therein. Fig. 5 is a front view showing the casing device as mounted upon the spindle 30 and engaged with operating strap connections, and Fig. 6 is a top plan view of Fig. 5.

Referring to the drawings —*a*— designates a bench. Arranged upon the top of said bench —*a*— are standards —*b*, *b*— each 35 provided with a shaft —*b'*— and a spindle —*k'*— at the free end thereof.

Said spindles —*k'*, *k'*— have flannels secured thereon and rings —*b*^o, *b*^o— mounted upon the same closely one on the other.

40 Passing over of each set of said rings mounted upon the spindles —*k*^o, *k*^o— are operating straps —*e*^o, *e*^o— having their ends provided with clip holders —*q*^o, *q*^o— and secured to the ends of flat portions —*r*, *r*— 45 projecting outwardly from oscillatory shaft —*l'*— which is arranged longitudinally to the bench —*a*— and extending forwardly to the standards —*b*, *b*. The shaft *E'* is provided with a crank at each end thereof and

50 operated by shaft —*E*— which is also provided with a crank at each end of the same and extending forwardly to the oscillatory shaft —*L*.

55 The shafts *l* and *l'* are connected together by connecting arms —*n'*, *n'*— which extend

between the ends of said shafts and each provided with an eyelet at each end thereof and loosely mounted upon the end portions of said shafts *l* and *l'*. A collar —*q*²— is secured upon the each free end portion of 60 said shafts and designed to keep said connecting arms —*n'*, *n'*— in position upon the end portions of said shafts.

Arranged longitudinally to the bench —*a*— are vertically extending supports —*e*, 65 *e*,— having their lower ends secured to the bench and supporting shafts *l* and *l'* upon their upper ends. Mounted upon said shaft —*l*— is a pulley —*l*^o— which is provided with a belt connection —*k*²— passing over 70 pulley *k*^o mounted upon upper shaft —*a*²—.

When shaft —*l*— operates, it will impart a backward and forward oscillatory movement to the shaft —*l'*—. Thus each strap 75 —*e*^o— of the spindles —*k'*, *k'*— will engage to perform the buffing operation by a backwardly and forwardly operating movement.

Each clip holder —*q*^o— is provided with coil pull-springs —*q*, *q*— having one of their ends secured to the rear ends of said clip holders —*q*^o— and the other ends provided with snap-hooks —*q*⁸, *q*⁸— and secured to the ends of the flat outwardly projecting portions —*r*, *r*— of the shaft —*l'*—.

Each standard —*b*, *b*— is provided with a 85 belt —*b*⁸— to drive the same and having a section —*n*— which is integral with the spindle shaft and provided with means to be raised and lowered.

It is preferable to have the standards for 90 this purpose in the form as shown.

Removably secured upon the free end portions of the spindles —*k'*, *k'*— of the standards —*b*, *b*— are collars —*v*^o— which are adapted to keep the straps —*e*^o, *e*^o— in their 95 position upon the spindles —*k'*, *k'*—.

The clip holder *q*^o comprises a base plate member provided with two vertically arranged integral pins —*a'*, *a'*— having a transversely extending shaft —*a*^o— upon 100 which is mounted a snap plate member and having coil-spring connections —*p'* and *p*^o— therebetween.

In Fig. 4 is shown a ring casing device which is designed to receive setting rings 105 —*u'*— within the same and adapted to be mounted upon the spindle *k'* and engaging with strap connections in the manner as shown in Figs. 1 and 2 and Figs. 5 and 6. A removable collar *v*^o is secured upon the end 110

portion of the spindle k' and designed to keep the casing device in position upon the spindle k' .

Thus having described the invention, what I claim as new and desire to secure by Letters Patent is:

1. In combination with a buffing bench having standards secured upon the top of the same and having spindles provided with flannels thereon, a horizontal crank shaft 10 forwardly to said standards and arranged longitudinally to said bench and having flat outwardly projecting portions arranged opposite to the spindles of said standards, an 15 operating strap for each of said spindles and passing over each of said spindles and having clip holders at the free ends thereof and connected to the outwardly projecting portions of said shaft, means to operate said 20 shaft and to impart backward and forward movement to said straps.
2. In combination with a buffing bench having standards secured upon the top of the same and having spindle shafts provided 25 with spindles, a crank shaft provided with sets of outwardly projecting portions extending forwardly to said standards and arranged longitudinally to said bench, a horizontal crank shaft forwardly to said shaft 30 and adapted to impart an oscillatory movement to the latter, a connecting arm between the ends of said shafts each provided with an eyelet at each end thereof and loosely mounted upon the end portions of said 35 shafts, vertically arranged supports for said shafts and having secured to said bench, means to operate said shafts, and collars secured upon the end portions of the same to keep the connecting arms in positions 40 upon the end portions of said shafts.
3. In combination with a buffing bench, having standards arranged upon the top of the same and having spindle shafts, an

oscillatory crank shaft forwardly to said standards and provided with sets of outwardly projecting flat portions arranged opposite to the spindles of said standards, operating strap connections between the spindles of said standards and the outwardly projecting portions of said shaft and clip 45 holders at the ends of said straps, each comprising a base plate member having a pair of vertically arranged integral pins supporting a shaft and having a snap plate member mounted upon the same, coil spring 50 connections forwardly and rearwardly of said vertically arranged pins between said base plate member and snap plate member, and coil spring connections from the rear ends of said clip holder to the flat outwardly 55 projecting portions of said oscillatory crank shaft.

4. In combination with a buffing bench having standards arranged upon the top of the same and provided with spindles, an 60 oscillatory crank shaft forwardly to said standards and having outwardly projecting flat portions arranged opposite to the spindles of said standards, a ring casing device for said spindles each comprising two sections connected together and adapted to receive setting rings therein and mounted upon said spindles, an operating strap, passing over said ring casing and having a clip 65 holder at each end thereof and connected to the outwardly projecting flat portions of said shaft, and a collar secured upon the end portion of each of said spindles of said standards to keep the operating straps in 70 position upon said ring casing.

In testimony whereof, I affix my signature in presence of two witnesses.

MARTIN JELALIAN.
